UNITED STATES PATENT OFFICE.

GUSTAV H. ROTH, OF BOSTON, MASSACHUSETTS.

RAILWAY-SIGNAL.

SPECIFICATION forming part of Letters Patent No. 241,885, dated May 24, 1881.

Application filed June 30, 1880. (Model.)

To all whom it may concern:

Be it known that I, GUSTAV H. ROTH, of Boston, Suffolk county, Massachusetts, have invented a new and useful Improvement in 5 Railway-Signal Apparatus, of which the following description, in connection with the accompanying drawings, is a specification.

This invention relates to railway-signal apparatus; and it consists, first, in providing at 10 suitable intervals along the road, signal apparatus adapted to show different signals successively, the said signals being automatically set in position to indicate danger by suitable mechanism when a train passes, and then when 15 the train passes the next signal apparatus the one in question is moved forward to show another signal, the different apparatus being so connected in series that as each one is set to "danger" by the train passing it sets the one before to show a new signal, which may be called 20 "No. 1," and this, in turn, sets the preceding one, already showing signal No. 1, to show No. 2, and it sets its predecessor to show No. 3, and so on for as many as may be desired in 25 a series.

The invention also consists in the combination, with a signal apparatus adapted to show a series of different signals in succession, of a 30 mechanical motor actuated by a weight or spring, and wound up by mechanism actuated by the passing train, and a detent controlled by an electro-motor until released by an electric current from the next signal apparatus, when it allows the motor to move the signal 35 apparatus and bring the following signal of the series into view; also, in the combination, with a clutch-box moved in one direction by a mechanical motor, of a signal-disk provided with a series of different signals on a shaft 40 provided with a second clutch-box, and with a weight or spring to move it in an opposite direction to that in which the first clutch-box is turned by the mechanical motor; also, in the combination, with a clutch, to be engaged 45 and rotated by a mechanical motor, of a shipper, adapted to be actuated by a passing train, to disconnect the said clutch and allow the disk to be rotated back with the shaft, and mechanism to remove the shipper and allow 50 the clutch to re-engage when the signal-disk

has reached its extreme backward position, in which it indicates danger; also, in a hand-operated signal, to be used in conjunction with the automatic block-signal, the said signals being pivoted concentrically, and a cord and pulley used to partially rotate the said signal to bring a red or danger signal into view in front of the automatic signal, and a pawl to hold it in this position, the said pawl being provided with a cord to trip it and release the 55 said hand-signal and allow it to be turned back by a spring or weight to again permit the automatic signal to show.

The invention also consists in placing at suitable intervals automatic circuit-breaking 60 instruments, containing circuit-breaking surfaces, set in motion by mechanism actuated by a weight or spring wound up by a passing train, a different number of breaks in the 65 circuit being caused by the circuit-breaking surfaces of the different instruments and the said different numbers preferably arranged in regular order—that is, the first station causing a single break, the second a double, the fourteenth a single break followed by a slight 70 pause and then four breaks, and so on. Thus, when the train passes each circuit-breaker, it winds the mechanism, which, in running down, breaks the circuit the appropriate number of times, indicating the number of the station, 75 and these breaks may, either with or without the interposition of relays, record on any desired signaling-instrument either visual or audible signals at any desired station on the road, to thus make known the position and progress 80 of the train.

The invention also consists in certain details of mechanical construction.

Instruments have previously been used whereby the train in passing operates a circuit-closer to close or break a circuit a single time, and the number of such operations indicates the number of stations passed by the train, or each of the said operations may cause a pointer or indicator to advance one step, and 90 thus indicate the advance of the train.

Figure 1 is a front elevation of a block-signal mechanism embodying my invention; Fig. 2, a face view of the signal-disk; Fig. 3, a sectional detail of Fig. 1 on line *x*, looking to 95 100

ward the right; Fig. 4, a section on the line *y*, looking to the left; Fig. 5, an elevation of the mechanism for the hand-operated signal; Fig. 6, a side view of an automatic circuit-breaking apparatus; Figs. 7 and 8, details thereof; Fig. 9, a front and side view of the arm carried by the train to actuate the different devices; Fig. 10, a diagram showing a series of automatic circuit-breakers to produce each a characteristic signal when a train passes; and Fig. 11 a side view of two of the toothed disks, which, when properly placed together, form the characteristic circuit-breaking surface.

The block-signal apparatus is operated primarily by a lever, *g*, and arm *j*, similar to that described in another application for United States patent, filed March 8, 1880, to which reference may be had. The arm *j* is connected by spring *j*¹ to a winding-lever, *q*, provided with a pawl, *q'*, to engage a ratchet, *r*, on a shaft, *r'*, and wind up a weight, 20, or spring, the said shaft *r* being connected by a ratchet and pawl in the usual manner with a wheel, *s*, loose on the said shaft, to cause the said wheel to rotate with it as the weight runs down. When the winding-lever *q* is not pulled down by the arm *j* it is held by the spring *q*² against a slot, 21, and in this position the pawl *q'* is disengaged from the ratchet *r* by the projection *q*³ on the frame-work, to allow the weight 20 to rotate the shaft *r'* and wheel *s*.

A detent-wheel, *s*², is provided with a pinion engaging the wheel *s*, and has a pin, 22, which is held by a detent-rod, *t*, supported in position to engage the said pin by the armature-lever *t'* of an electro-magnet, *t*². When the electro-magnet is magnetized by an electric current controlled by a circuit-closer at the next station, as hereinafter described, the detent-rod falls or is depressed by a spring to release the detent-wheel, to allow it to make one revolution, when, as the said circuit is only closed momentarily, the detent-rod *t* is again in position to stop it.

The wheel *s* is provided with a series of projections, 23, shown as six in number, so arranged that they will advance one step at each revolution of the detent-wheel *s*², to bring one of said projections into the position previously held by one in advance, and in such movement to engage the end of and depress a lever, *u*, pivoted at 24, and connected by a cord, 25, with a pulley, *v*, loose on a shaft, *w*, carrying the signal-disk *x*, and supported at one end in a bearing, *y*, in which it is free to move longitudinally a short distance, and at the other end in a clutch-box, *z*, loose on the said shaft *w*, and itself guided in a bearing, 26, which prevents longitudinal movement of the said clutch-box. A corresponding clutch-box, *w'*, secured to the shaft *w*, engages the one *z* when the said shaft is in its normal position, shown in full lines, Fig. 1, it being pressed by a spring, 27, against the thin portion 28 of a shipper, *w*².

The loose clutch-box *z* is provided with a

ratchet-wheel, *z'*, (see Fig. 3,) to be engaged by a pawl, 29, on the loose pulley *v*, such connection causing the rotation of the pulley *v* in the direction of the arrow caused by the depression of the lever *u* to be transmitted to the clutch-box *z*, and by it to the one *w'* when in engagement therewith and to the signal-disk *x*.

Upon the clutch-box *z* is a large ratchet-toothed wheel, *z*², having a tooth to correspond to each signal on the signal-disk, and the movement of the lever *u* is sufficient to move the said wheel *z*² forward one tooth to bring a new signal on the disk into view, after which it is held by the pawl *z*³, so that when the projection 23 has passed over the end of the lever *u*, and the latter is raised by the spring 30 or weight, the pawl 29 of the pulley *v* slips over the teeth of the ratchet *z* into position to again move the clutch and signal-disk forward at the next depression of the lever *u*.

The signal-disk shown in Fig. 2 is inclosed in a case having an opening corresponding in size and position to the circle on the said disk marked *R*, the said circle being in practice 90 made red to indicate danger. At each depression of the lever *u* the successive circles, marked 1 2 3, are brought into the position shown at *R*, to be exhibited through the opening in the casing, and the signals will be 95 distinguishable from one another, either by color or preferably by numbers, as shown, the one marked *W* being white or else open space.

The clutch-box *w'* is provided with a drum, over which is suspended a weight, 31, which tends to rotate the said drum and signal-disk in an opposite direction to that just described as the forward direction caused by the weight 20 and lever *u*. The weight 31 is so light as to be overcome by the weight 20 and wound up 105 in what may be called the "forward movement" of the signal-disk.

When the train passes and winds the weight 20, as before described, the arm *j* also acts on the spring *j*¹ to depress the shipper *w*² and bring it to the position shown in dotted lines, Fig. 1, where it is held by the pawl 32 pivoted at 33 and pressed by a spring, 34, to engage the top 35 (see Fig. 3) of the shipper *w*². When thus depressed the shipper *w*² throws the shaft *w* and clutch-box *w'* to the left, as shown in dotted lines, disengaging it from the clutch-box *z*, and allowing it and the connected signal-disk to rotate back under the stress of the weight 31 until, just at the end of the said rotation, the inclined projection 38 on the disk 39, carried by the clutch-box *w'*, strikes the inclined end 40 of the releasing-bar and slides it longitudinally in its bearings 41 42 to strike a pin, 43, on the pawl 32, and push back the said pawl to release the shipper *w*², which is then raised by the spring 44 to allow the clutch *w'* *z* to re-engage. The releasing-bar is flattened at 45 to prevent it from turning in the bearing 42. (See Fig. 3.)

The backward rotation of the signal-disk, under the influence of the weight 31, is stopped

when in position to display a signal, R, by a pin, 46, (see Fig. 4,) on the disk 39, engaging a stop, 47, pivoted, as shown, to allow its stopping end a movement equal to the diameter of the pin 46, to thus admit of a complete forward revolution of the signal-disk before it is again stopped by the same pin on the other side of the said stop, as shown in dotted lines, the end 40 of the releasing-bar and the inclined 10 projection 38 being cut away, as shown at 48, to allow them to overlap when they meet in the forward rotation.

The apparatus at all signal-stations is the same, and the electro-magnet t^2 is magnetized, 15 to release the detent-wheel s^2 and allow the signal-disk to be rotated to bring a new signal into view by an electric current, when the circuit is closed, from the next signal apparatus by a circuit-closer operated by the signal 20 mechanism.

As herein shown, the circuit is open between the wires 50 51, and closed when the wire 51 is pressed down into contact with the wire 50 by either of the circuit-closers 52 or 53, operated 25 by the disk 39 in its rotation with the shaft w and signal-disk x .

The circuit-closer 52, pivoted at 54, is provided with a foot, 55, to be struck by the projection 56 on the disk 39, in the backward rotation thereof, under the influence of the weight 31, and pressed against the wire 51 to close the circuit and magnetize the electro-magnet t^2 at the last signal-station preceding. When the projection 56 passes the foot 55 in the forward rotation of the disk 39 it merely swings the circuit closer away from the wire 51, which has no effect on the circuit.

The disk 39 has also on its periphery a series of pins 57, one corresponding to each signal of 40 the disk x , so placed that each time the said disk is moved forward by the lever u , as before described, to show a new signal, one of the said pins 57 strikes the foot 58 of the circuit-closer 53 pivoted at 58, and causes it to press 45 the wire 51 against the wire 50 to close the circuit. In the backward rotation of the disk 39 these pins are moved out of line with the foot 58, and consequently do not touch it; but the said circuit-closer is not adapted to be 50 operated except by moving the foot 58 to the left in Fig. 4, as caused by the forward rotation of the disk 39.

The operation of these block-signals is as follows: A train arriving from the terminal 55 station passes the first signal, which may be called A, and disconnects the clutch $w' z$, allowing the signal to be turned back by the weight 31, to exhibit the first or danger signal, R, and at the end of its movement again allows 60 the clutch to engage, and, at the same time, the weight 20 is wound up. When the train in its further progress arrives at the next station, or station B, the same operation is performed, and the said signal B, in turning back 65 to show the signal R, operates the circuit-closer 52 to magnetize the electro-magnet t^2 at

station A, release the wheel S^2 , depress the lever a , and move the signal-disk forward one step to show the second signal, marked 1. When the train arrives at station C that signal is set to display R, as just described, and in so doing operates the electro-magnet at 70 station B, where the signal is advanced from R to 1, as just described for station A, and in so advancing one of the pins 57 operates the circuit-closer 53 to magnetize the electro-magnet at station A and allow the signal to be moved forward another step—that is, to display the signal 2. Thus, as the train passes each successive signal it sets it to danger, and all the 80 preceding signals are advanced one step, so that the engineer of any following train is definitely informed of the position of a train in advance. Thus, if the signal W or a blank is shown, he knows that five or more sections 85 intervene between his train and the one in advance, or if one of the numbered signals is displayed, he knows that the same number of sections intervene, and if, as he advances, he finds the signals in the descending order of 90 numbers, as 4, 3, 2, 1, R, he will know that a train is remaining, from some cause, in the next section, and will govern his train accordingly.

For single-track purposes an independent 95 signal may be placed in advance of each station, and may be set ahead from such proceeding station, in the manner hereinbefore described, for the one in the rear, but in such signals the positions of the circles should be 100 changed, the disk being moved forward to indicate danger when operated from the proceeding station, and set back to show a blank or "safety" when the train passes it.

A hand-operated signal-disk, 60, is used in 105 conjunction with the automatic one x , just described, being pivoted concentrically therewith and provided with an opening which, in normal position, allows the signals of the disk x to show through. This signal-disk 60 is connected with a pulley, 61, which may be operated by pulling the cord 62 to advance the signal-disk and display a red or danger signal in front of the disk x , and is retained in this position by a pawl, 63, engaging the tooth 64. When 110 desired to remove this danger-signal, the pawl 63 is tripped by pulling the cord 65 and the signal turned back by the stress of a spring, 66, or weight. The movement of the disk 60 in each direction is limited by the stop-pins 67. 115

Fig. 6 represents the automatic circuit-breaking apparatus, which is operated by a lever, g , as hereinbefore described. In Fig. 6 the lever is shown depressed by a passing car, h' . The arm j is connected by a spring, j^5 , and 120 cord with a pulley, 70, on a shaft, 71, carrying the circuit-breaking disk 72, provided with teeth 74, herein shown, spaced to send the signal 14.

A circuit-breaker, 75, pivoted at 76 and normally held by a spring, 77, in contact with a wire, 78, to close the circuit, is provided with 130

a pawl, 79, pivoted at 80, its lower end being in position to be struck by the teeth 74, and free to move to the right independently of the circuit-breaker 75. When the train depresses 5 the lever *g* the pulley 70 and wheel 72 are rotated until stopped by the pins 82 83, the teeth 74 then swinging the pawl 79 toward the right on its pivot 80 without disturbing the circuit-breaker 75. In this movement the shaft 71 10 winds up a spring or weight, which, as soon as the lever *g* is released, rotates the shaft 71 back, and in such rotation the ratchet-wheel 84 thereon engages the pawl 85 and rotates the wheel 86 connected with the escapement 87, which 15 gives the shaft 71 a uniform motion. In this uniform backward rotation the teeth 74 pass the pawl 79 toward the left, and move it and the circuit-breaker on the pivot 76 into the position shown in dotted lines, breaking the circuit between it and the wire 78 once as each tooth 74 passes, and these breaks, signalized or recorded by any suitable instrument at any 20 desired station, indicate that a train has just passed station fourteen.

The circuit-breaking wheel is composed of 25 two plates, 72 73, the one 72 having three teeth and the one 73 one and three to represent thirteen. By this construction it will be seen that by sliding one plate on the other several other numbers can be formed, as four, six, 30 thirteen to sixteen, and others.

Fig. 10 represents three consecutive signal-stations, the circuit normally passing through the main wire 78 to the circuit-breaker 75, in contact therewith, and connected with the main wire 78, leading to the next station. The circuit-breaking wheels are adapted to give the signals 12, 13, 14, respectively, the circuit-breakers 75 being properly vibrated to break 40 the main circuit 78, in which suitable batteries and relays may be placed, as will be well understood.

The levers *g* may be operated in any usual way, as by the wheels; but I prefer to use a 45 detachable arm, *k*, (see Fig. 9,) provided with a friction-roller, *k*², and adapted to be secured in suitable lugs, *k*³, fastened at a convenient point on one of the vehicles of the train, preferably the last one, thereby properly operating 50 the signals to afford security in case the train breaks apart.

I claim—

1. In an automatic railway-signal system, a series of three or more signal-stations, each station having a signal apparatus adapted to show 55 a series of three or more different signals, and mechanism, substantially as described, actuated by a passing train to display the first or danger signal when a train passes the said station and connections between the said stations, whereby each movement of a signal at one station causes a corresponding movement in the signal of the preceding station, and the successive signals of the series displayed at each 60 station as the train in its progress passes the

successive stations in advance thereof, substantially as and for the purpose specified.

2. A railway-signal apparatus adapted to show a series of three or more different signals in succession, and a mechanical motor therefor wound up by a passing train, combined with a detent controlled by an electro-magnet and a series of circuit-controlling devices operated by the apparatus at the next signal-station, one corresponding to each signal there- 70 of, to release the motor and allow it to bring a new signal into view each time that a new signal is shown at the said next station, substantially as described.

3. A visual signal and mechanical motor to 80 move it to show a series of different signals thereon in succession, and a retractor therefor acting in opposition to the said motor, combined with mechanism, controlled by a passing train, to disengage the said motor and allow the said retractor to set the signal back to show the first signal of the series, substantially as described.

4. A rotatable signal-disk provided with a series of different signals, a mechanical motor 90 and clutch to connect it with the said disk, to cause the said motor to rotate the disk forward to display a new signal each time the motor is released and allowed to operate, combined with a shipper, operated by a passing train, to dis- 95 engage the said clutch and allow the signal-disk to be turned back under the stress of a retracting weight or spring, and a releasing device to release the said shipper and allow the clutch to re-engage when the said disk has 100 reached the end of its backward movement, substantially as described.

5. In a railway-signal apparatus an automatically-operated signal-disk provided with a series of signals, to be successively displayed, 105 combined with a hand-operated signal-disk pivoted concentrically therewith and adapted to be moved to place a danger-signal in front of and to conceal the automatic signal, or to bring an opening in position to allow the said automatic signal to be displayed therethrough, substantially as described.

6. A pivoted signal-disk and a pulley on its axis, and a cord upon said pulley to rotate it and the signal-disk, and a pawl to retain it in 115 position to display a signal, combined with a cord to trip the said pawl, and a retractor to rotate the signal-disk back to its original position when the pawl is tripped, substantially as described.

7. In a railway-signal apparatus, a series of 120 automatic circuit-breaking instruments placed at suitable intervals along the road and actuated by mechanism wound by the passing train, each adapted to cause a definite number of 125 breaks in the circuit different from the others, whereby the instrument operated, and consequent position of the train operating it, is definitely designated by the signal, substantially as and for the purpose described.

8. The signal-disk and its shaft to rotate forward and backward, provided with a stop-pin to limit its movement in either direction, combined with a stop pivoted to allow the said signal to make an entire revolution, substantially as described.

9. A circuit-breaking surface composed of two plates each provided with circuit-breaking teeth, whereby different numbers of breaks can be formed by sliding one plate on the other to

cause the teeth of one plate to act with or independently of those on the other plate, substantially as described.

In testimony whereof I have signed my name to this specification in the presence of two subscribing witnesses.

GUSTAV H. ROTH.
